DESIGN FOR A COMPORT OR SIMILAR ARTICLE

Carl W. Gustkey, Wheeling, W. Va., assignor to Imperial Glass Corporation, Bellaire, Ohio, a corporation of Ohio

Application March 25, 1941, Serial No. 99,872

Term of patent 14 years

To all whom it may concern:

Be it known that I, Carl W. Gustkey, a citizen of the United States of America and resident of Wheeling, county of Ohio, and State of West Virginia, have invented a new, original, and ornamental Design for a Comport or Similar Article, of which the following is a specification, reference being had to the accompanying drawing, forming part thereof, in which:

Figure 1 is a side elevational view of a comport or similar article, showing my new design; and Figure 2 is a top plan view of the same.

I claim—

The ornamental design for a comport or similar article, substantially as shown.

CARL W. GUSTKEY.
